UNITED STATES PATENT OFFICE.

AXEL G. GULBRANSEN, OF CHICAGO, ILLINOIS, ASSIGNOR TO GULBRANSEN-DICKINSON COMPANY, OF CHICAGO, ILLINOIS, A CORPORATION OF ILLINOIS.

PIANO-PLAYER ACTION.

1,349,273.

Specification of Letters Patent. Patented Aug. 10, 1920.

Application filed June 3, 1915. Serial No. 31,815.

To all whom it may concern:

Be it known that I, AXEL G. GULBRANSEN, a citizen of the United States, residing at Chicago, in the county of Cook and State 5 of Illinois, have invented a certain new and useful Improvement in Piano-Player Actions, of which the following is a full, clear, concise, and exact description, reference being had to the accompanying drawings, 10 forming a part of this specification.

My invention relates to automatically operated musical instruments and has to do particularly with what are known as player pianos or piano players. It will be obvious 15 that the device of my invention may be applied to organs as well as pianos and, in fact, to any musical instrument or other device operated in an analogous way. It will be understood that my invention is concerned with what has become known as the 20 "action"—that is, the operating means and need not, therefore, be limited to its application to any particular instrument.

In order to simplify this description I 25 shall explain my invention and apply it to a player piano, particularly since some of the more limited features are really limited to a player piano and since, in general, the advantages which my invention secure are 30 most pronounced in its application to such a structure.

As before indicated, my invention has particularly to do with the "action," which term has become used in the art to signify 35 the structure comprising the playing unit and the immediately associated parts. My invention has to do with that class of automatic instruments which is operated pneumatically and therefore these operating units or devices will be seen to be in the form of 40 small bellows commonly known as "pneumatics." One of these pneumatics is provided for each note on the piano to be struck and my invention is concerned with the construction of these pneumatics, the valve 45 mechanism therefor, the connections to the power plant and the general assembly of the structure which may be termed a "stack."

It is the object of my invention to provide 50 a radically simplified, compact, and "tight" structure. By reason of the simplicity of the structure and the minimum number of parts employed, the possibility of 55 leaks is practically, if not absolutely, elimi-

nated. What has become known in the art as the "vacuum chamber" of the stack or action has been practically dispensed with, by means of my invention, and the resulting directness of the connection between the operating pneumatics and the power plant further contribute to the air tight feature of the structure and the effectiveness and 60 simplicity of the operation.

My invention also relates to the mounting 65 of the action in the case, as will be described.

My invention is illustrated in the accompanying drawings in which—

Figure 1 is a front elevational view of the upper part of a player piano, part of the 70 casing being removed, showing the application of the structure of my invention thereto.

Fig. 2 is a more or less diagrammatic side view of the arrangement shown in Fig. 1.

Fig. 3 is a rear elevational view of the ac- 75 tion.

Fig. 4 is an end elevational view of the action, part being shown in cross-section so as to clearly reveal the interior construction.

Fig. 5 is a detail view of a valve stem ar- 80 rangement which will be referred to.

Fig. 6 is a plan view of a portion of the action, part being shown in section.

Fig. 7 is an end view of the action and the 85 associated casing parts, and

Figs. 8 and 9 are further detail views, Fig. 9 being a section on line 9—9 of Fig. 8.

Referring first to Figs. 1, 2, 7, 8 and 9, it will be seen that the piano case is shown at 7, the key bed of the piano being shown 90 at 8 and side pieces being provided at 9, 9. The action of my invention is supported by the side pieces 9, 9, it being seen that the channel board 10, which I shall describe more specifically later, is secured to the side 95 pieces 9, 9, by means of the screws 11, 11. It will be seen that this arrangement provides for the ready removal of the channel board and since the operating pneumatics are all carried by this channel board, it will be seen 100 that the entire action may be immediately removed. The compactness of the action permits of it being so mounted that the keys K can be removed without removing the action.

Hinged to the top of the channel board 10 by means of the hinges 12, 12, is a bracket board 13, the nature of which is more clearly illustrated in Figs. 2 and 7. The bracket board 13 carries the roller box 14 in which 110

the rollers 15 and 16 and the tracker board 17 are provided. The rollers are operated by means of pneumatic motor 18, the details of which I am not concerned with here. In 5 order to simplify this description and illustration, I have shown the motor and the roller box arrangement in a most general way. It will be sufficient to point out that the tracker board 17 is connected with the 10 action in a manner to be described presently.

A metal bracket 19 is secured to the back of the channel board and extends upwardly to engage the bracket board 13, one of these metal brackets being provided at each end 15 of the channel board. The end of the bracket 19 is provided with a screw 20 upon which a thumb-nut 21 is screwed and it will be seen that this arrangement locks the bracket board 13 in positive position relative 20 to the channel board. When the thumb-nuts 21 are loosened, the roller box and the motor support, which is also mounted upon the bracket 13, may be swung forwardly into the position shown in Fig. 7. A linkage arrangement, comprising the links 22, 22^a and 22^b, pivoted together at *p*, *p*, is connected between the back board 23 of the piano and the roller box so that the roller box may be positively supported in either its inner or 25 outer position, its inner position being the normal position and its outer position being that which affords access to the mechanism behind the roller box. The links are pivoted to the back board at 23^a and to the roller box at 23^b. Fig. 9 shows the linkages in plan, one of the links being provided with a foot 30 23^c abutting the back board.

Referring now to Figs. 3 to 6, inclusive, it will be seen that the channel board 10 is a 40 single integral member extending from end to end of the casing and consequently extending entirely across all the striker rods which, in the piano construction, are disposed behind it, as indicated, in Fig. 5. This 45 single integral member 10 is mortised at the rear side of the top throughout the entire length thereof, as illustrated at 24, and a series of channels arranged longitudinally of the board pass down from this mortised portion to the various pneumatic mechanisms, as will be described, these channels being indicated at 25. For each channel 25 a smaller channel 26 is also provided, each channel 26 being preferably in the same transverse plane 50 with its corresponding channel 25, as illustrated in Fig. 6. This channel 26 is drilled down from the very top of the board, as illustrated in Fig. 5, and the top of the channel is plugged by means of the member 27. A 55 strip 28 is secured, preferably by means of glue, and other means in addition probably, to the rear face of the board 10 in the mortised portion and a board 29 is secured over this strip and the rear face of the board 10, 60 as illustrated in Fig. 4, so as to form the

longitudinal channel 30 which runs from end to end, the end however being properly plugged up or stopped up so as to make the channel 30 air-tight. It will thus be seen that the channel 30 is in direct communication 70 with all the passage-ways 25 which lead downwardly therefrom.

A transverse channel 31 is drilled through the board 29, the strip 28, and part of the board 10 into each of the passage-ways 26 and a tube, preferably of rubber, illustrated at 32, extends from each of the channels 31 to a corresponding opening in the tracker board 17. It will be understood that the passing of the note sheet 80 over the tracker board controls the momentary or temporary admission of air to the passageway 31 and the connected parts below.

The actuating pneumatics are arranged 85 in three rows and are staggered in their vertical relation to each other so as to bring each of them in proper registry with the corresponding striker rods of the piano mechanism. Three boards, each of which 90 may be termed a "channel and valve board," are secured edgewise to the rear face of the channel board 10; that is, the channel and valve boards lie in horizontal position and extend rearwardly from the channel board 95 10, being placed one above the other. These channel and valve boards extend nearly the entire length of the channel board 10 and each of them supports an entire row of actuating pneumatics. The channel and valve boards are illustrated at 33 and it will 100 be seen that each of them is secured to the rear face of the channel board 10 by means of long screws 34, 34, at each end thereof, these channel and valve boards being preferably also firmly and tightly glued to the 105 face of the channel board 10.

Each of the actuating pneumatics comprises a stationary board 35 and a movable board 36 which is hinged at its forward end 110 to the stationary board 35 by means of a leather hinge 37, the two boards being united to form a collapsible air-tight chamber by means of the bellows cloth 38. The movable board 36 has a rearward extension 39 115 for engagement with the abutment member 40 carried by the corresponding striker rod 41. A description of one of these pneumatics will suffice, since all the actuating pneumatics are of the same construction, 120 each being disposed in position to actuate its corresponding striker rod.

Each of the boards 35 is firmly secured 125 in proper position to the under side of the proper valve and channel boards 33, as clearly illustrated in the drawing. By reference to Fig. 4, it will be seen that each of the boards 35 provides a diaphragm chamber 42 which is covered by the diaphragm 43, this chamber 42 being connected with its 130

corresponding passageway 26 by means of the L-shaped passageway 44 in the board 35, the passageway 45 in the board 33 and the passageway 46 in the board 10. The dia-

5 phragm 43 is shown in its lowermost position in Fig. 4 and it will be understood that the space above it is ample for its movement to the opposite extreme. In axial alinement with the diaphragm 43 the board 33 is pro-

10 vided with an opening 47 and a valve chamber 48. A valve seat ring 49 is disposed tightly in the top of the opening 47, this ring being preferably of metal so as to form an effective valve seat. A head 50 engaged

15 by, and either secured or not secured to the diaphragm 43 is carried by a valve stem 51 which passes upwardly through the opening 49 and through the valve seat ring and at the top is provided with the valve mem-

20 ber 52. This valve stem 51 is illustrated in detail in Fig. 5 where it will be seen that it is effectively guided in the valve seat ring while at the same time providing for ample air passage thereby. It will now be under-

25 stood that when the diaphragm is in its lowermost position, the valve 52 rests upon the valve seat ring and when the dia-

30 phragm is in its uppermost position the valve 52 is raised so as to make communica-

tion. This position is assured by gravity and also by the fact that the passageway 26 is bled from the channel 30 through a very restricted aperture 59 in a metal thimble 60 secured in an opening 61, drilled in

70 the board 10 between the passageways 26 and 30. The thimble is inserted through an opening 62 which, after construction, is closed by means of a strip of air-tight mate-

75 rial indicated at 63. As indicated in Fig.

3, the passageway 30 is connected with the power plant by means of a suction tube 64, this being diagrammatically shown in Fig.

2 where the dotted line 65 indicates the con-

80 nection to the power bellows 66, now well known in the art. It will thus be seen that a constant vacuum is maintained in the pas-

85 sageway 26 and the connecting passageways, including the diaphragm chamber below the diaphragm 43 so long as air is not admitted

85 through the tracker bar into the correspond-

90 ing passageway 31. Just as soon as air is admitted through an opening in the note-

95 sheet, pressure is transmitted down through the passageways 31, 26, 46, 45, 44 and since

95 a constant vacuum is maintained above the diaphragm by way of the passageways 47,

100 53, 54, 25 and 30, the diaphragm rises to its uppermost position. This changes the posi-

105 tion of the valve 52. Normally this valve

105 rests upon its seat and the actuating pneu-

110 matic is connected directly with the atmos-

115 phere through the passageway 55, the valve

120 chamber 48 and the opening 57. When,

125 however, the valve 52 is moved to its upper-

130 most position, it engages the under side of the disk 56 and closes the opening 57. This shuts off the access of the atmosphere and directly connects the actuating pneumatic

135 with suction. It will be obvious that this

140 collapses the pneumatic and raises the ex-

145 tension 39 so that it will in turn raise the abutment member 40 and consequently the

150 striker rod 41 to sound the corresponding

155 note. When the admission of the atmos-

160 phere to the passage 31 has again been cut

165 off by the action of the note sheet, the suc-

170 tion again operates through the aperture

175 59 to reduce the pressure below the dia-

180 phragm 43. This again equalizes the pres-

185 sure on both sides of the diaphragm and

190 gravity brings down the valve 52 so as to

195 cut off the connection between the suction

200 means and the actuating pneumatic and,

205 instead, connects the actuating pneumatic

210 with the atmosphere, so as to permit its ex-

215 tension. An adjusting screw 64^a is pro-

220 vided to determine the throw of the mov-

225 able board of the actuating pneumatic.

230 It will be seen that the channel board 10

125 is readily constructed, being simply a matter

130 of drilling a system of channels so that the

135 connection to the suction means is secured

140 without the intervention of the usual vac-

145 um chamber. It will also be seen that the

150

boards 33, 33, are readily constructed and that the number of parts is at a minimum. I have found by experiment and test that with this kind of a structure the actuating 5 pneumatics operate with especial directness and efficiency.

By my invention the moving medium between the power plant and the actuating pneumatic is at a volumetric minimum, that 10 is, the capacity of the connecting passages is at a minimum and therefore the total expansion possible is reduced to a minimum. Packed joints are entirely eliminated and the boards 33, 33, are effective in keeping 15 the board 10 from warping out of shape.

I claim as new and desire to secure by Letters Patent:

1. In combination, a channel board having a plurality of independent channels therein, 20 a longitudinal channel and a plurality of channels extending from and disposed below said longitudinal channel, a plurality of actuating pneumatics each having a passageway connecting with one of said third named 25 channels, a valve in each said passageway, a diaphragm for operating each said valve, and a diaphragm chamber adjacent each said diaphragm, each diaphragm chamber being connected with one of said first named 30 independent channels.

2. In combination, a channel board having a plurality of independent channels therein, a longitudinal channel and a plurality of channels extending from said longitudinal 35 channel, said longitudinal channels lying above and said third named channels lying below a given plane, said board being bored to form the independent channels and third named channels and being mortised to form 40 the longitudinal channel, a number closing said mortise, a plurality of actuating pneumatics each having a passageway connecting with one of said third named channels, a valve in each said passageway, a 45 diaphragm for operating each said valve, and a diaphragm chamber adjacent each said diaphragm, each diaphragm chamber being connected with one of said first named independent channels.

3. In combination, a channel board having a plurality of independent channels therein, a longitudinal channel and a plurality of channels extending from and disposed below 55 said longitudinal channel, a plurality of actuating pneumatics each having a passageway connecting with one of said third named channels, a valve in each said passageway, said pneumatics being normally open to the atmosphere and said valve operating to close 60 off the atmosphere when it moves to open said passageway, a diaphragm for operating each said valve, and a diaphragm chamber adjacent each said diaphragm, each diaphragm chamber being connected with one 65 of said first named independent channels.

4. In combination, a channel board having a plurality of independent channels therein, a longitudinal channel and a plurality of channels extending from and disposed below said longitudinal channel, a plurality of 70 actuating pneumatics each having a passageway connecting with one of said third named channels, a valve in each said passageway, a diaphragm for operating each said valve, a diaphragm chamber adjacent each said 75 diaphragm, each diaphragm chamber being connected with one of said first named independent channels, and a bleeder between each independent channel and said longitudinal channel. 80

5. In combination, a channel board having a plurality of independent channels therein, a longitudinal channel and a plurality of channels extending from and disposed below said longitudinal channels, a 85 plurality of actuating pneumatics each having a passageway connection with one of said third named channels, a valve in each said passageway, a diaphragm for operating each said valve, a diaphragm chamber adjacent each said 90 diaphragm, each diaphragm chamber being connected with one of said first named independent channels, and an opening between each independent channel and said longitudinal channel, an 95 outer access aperture in line with said opening, and a thimble providing a restricted vent disposed in said opening.

6. In combination a channel board having a plurality of independent channels therein, 100 a longitudinal channel and a plurality of channels extending from and disposed below said longitudinal channel, each of said independent channels being connected with a tracker bar opening and said longitudinal 105 channel being connected with a source of suction, a plurality of actuating pneumatics each having a passageway connecting with one of said third named channels, a valve in each said passageway, a diaphragm for 110 operating each said valve, and a diaphragm chamber adjacent each said diaphragm, each diaphragm chamber being connected with one of said first named independent channels. 115

7. In combination a channel board, a board secured to and extending laterally therefrom, a plurality of similar valve chambers and respective passageways leading thereto and therefrom in said second named board, 120 a plurality of pneumatics, each comprising a stationary board and a movable board, the stationary board of each being secured to the laterally extending board, a diaphragm chamber in each said stationary board, a 125 diaphragm in each said diaphragm chamber, and a valve carried in each said valve chamber and engaged and operated by said diaphragm to control said passageways.

8. In combination, a channel board, a 130

board secured to and extending laterally therefrom, a plurality of similar valve chambers and respective passageways leading thereto and therefrom in said second 5 named board, a plurality of pneumatics, each comprising a stationary board and a movable board, the stationary board of each being secured to the laterally extending board, a diaphragm chamber in each said 10 stationary board, a diaphragm in each said diaphragm chamber, a valve carried in each

said valve chamber and engaged and operated by said diaphragm to control said passageways, each said valve chamber having an atmosphere inlet and said valve operating to alternately connect said pneumatic with the atmosphere and with a channel in 15 said channel board.

In witness whereof I hereunto subscribe my name this 29th day of May, A. D. 1915. 20

AXEL G. GULBRANSEN.
